F. BREITENFELL

WRENCH

Filed Jan. 14, 1924

FIG. 1.

FIG. 2.

Frederick Breitenfeld, Inventor

By his Attorney *Ott Urich*

UNITED STATES PATENT OFFICE.

FREDERICK BREITENFELD, OF NEW YORK, N. Y.

WRENCH.

Application filed January 14, 1924. Serial No. 685,974.

To all whom it may concern:

Be it known that I, FREDERICK BREITENFELD, citizen of the United States of America, residing at city, county, and State of 5 New York, have invented new and useful Improvements in Wrenches, of which the following is a specification.

My invention relates to improvements in wrenches and has particular reference to 10 the type of wrench having an adjustable jaw operated by means of a separate handle member.

The ordinary flat-jawed wrench requires the tightening of the jaws around the bolt 15 head or nut by means of a screw, and once adjusted in some required position the jaws remain fixed until separated or forced further together by further adjustment of the screw. In the actual operation of such a 20 wrench, one of two things may occur. Having tightened the jaws of the wrench onto a nut, the operator, after turning the wrench through a certain angle, will have to loosen the jaws slightly in order to 25 get a grip on two other faces of the nut and then retighten the jaws before exerting a turning force again, and this process will have to be repeated a number of times, since a wrench is never turned around in 30 a complete arc of 360 degrees or over. Ordinarily, however, the jaws will be originally tightened just sufficiently to leave a slight clearance between them and the nut faces. This allows changing the grip from 35 one set of nut faces to another without unscrewing the jaws each time, but it means that the jaws are turning the nut by a pressure upon the nut edges, which is injurious to the nut, especially in the case 40 of nuts of small size and of a soft material. Should the edges become rounded by such constant wear or by a probable slipping of the wrench jaws, the nut becomes very difficult to manipulate and may be 45 come useless.

My invention avoids these disadvantages by providing means whereby the mere pressure of the operator upon the wrench handle as he starts to turn the nut after gripping it, will serve to force the jaw faces together and thus pinch the nut faces firmly. In changing his grip upon the nut, the jaws will loosen slightly and sufficiently 50 by the mere fact of his ceasing to exert a turning force upon the handle.

Further advantages of my construction

lie in the ability to change the distance between the jaws by merely pushing them together or pulling them apart, thus doing away with the usual turning of the screw; 60 in the fact that my wrench must of necessity be used in the proper manner, i. e., with the turning force upon the handle exerted in the direction of the open space between the jaws; and in its great simplicity of design, which results in economy of manufacture. 65

In Fig. 1, I have shown a perspective view of my wrench.

Fig. 2 is an elevation partly in section. 70

Referring to the drawings, 1 denotes an outside or fixed jaw having an integral shank portion 6 provided with a plurality of cut teeth 9 disposed along its upper edge adjacent the rear end thereof. An 75 inside or movable jaw 2 is slidably mounted on the shank 6 and the walls of the opening embracing the shank are of a size to permit very slight relative movement of the two members. The jaw 2 is controlled 80 in its movement against the face of a nut by means of a handle 3 comprising a grip portion terminating at its forward end in an upturned portion provided with an opening to receive the shank 6, as clearly illustrated in Fig. 2. The upper rear edge of 85 this opening is curved downwardly to provide a tooth 4 adapted to engage the teeth 9 of the shank; the tooth being normally held in engagement with the teeth 9 by 90 means of a flat spring 5, which is disposed in a projected under portion of the opening for the shank, and which yieldably bears against the latter to force the two members together. The nose 8 of the upturned portion of the handle 3 is substantially 95 a curved edge surface described by a curve having its center point located somewhere in the rear of the tooth 4 so that as the handle moves about the fulcrum point 100 of tooth 4 the curved bearing surface or nose will move into closer relation with the fixed jaw 1 and against the rear surface of the movable jaw 2. A projection 7 at the end of the shank 6 prevents the handle 105 3 from slipping off the shank while the tooth 4 is disengaged and the handle is being shifted.

Thus in operation the handle is merely pushed forward, pushing the movable jaw 110 ahead of it, until the nut is gripped. Upon commencing to turn the handle in the usual

way, the handle will pivot around tooth 4 and very evidently a great forward pressure will act at point 8, forcing the jaws together and pinching the faces of the nut. 5 It is not contemplated that the handle should ever deviate any substantial amount from its practically parallel position relative to the shank 6. A very small movement at the end of the handle will take up 10 any play between the jaws and the nut faces. This play of course will never exceed the distance between two teeth.

It is quite conceivable that by shaping the jaw faces other than flat, or by cutting 15 teeth therein, this wrench may be adapted to be used for pipes and other circular objects, without departing from the spirit of the invention.

What I claim is:

- 20 1. In a wrench of the character described, the combination of a fixed jaw having a shank, a jaw movable with respect to the first, and means slidably mounted on said shank and movable relatively of both jaws 25 to exert pressure against the movable jaw in the direction of the fixed jaw.
2. In a wrench of the character described, the combination of a fixed jaw having an integral toothed shank, a second jaw adjustable over said shank, and a separate handle member independently adjustable over said shank and having a projection to

engage and fulcrum in the toothed portion of the shank and a bearing surface to move against said second jaw to exert pressure 35 against the latter in the direction of the fixed jaw.

3. A wrench as claimed in claim 2, including a spring member disposed between the shank of the fixed jaw and the handle 40 member to hold the said projection in engagement with the toothed portion of the shank, substantially as described.

4. A wrench, comprising a fixed and a 45 movable jaw, and a separate handle member independently adjustable relatively to both jaws and having a bearing surface movable against the movable jaw to exert pressure against the latter in the direction of the fixed jaw.

5. A wrench as claimed in claim 2, in which the said bearing surface comprises a curved surface, the center point of which is disposed rearwardly of the fulcrum point of the projection, whereby rotary movement of the handle with respect to the shank will cause the curved surface farthest from the fulcrum point to advance in the direction of the fixed jaw and against the movable jaw. 55

In testimony whereof I affix my signature.

FREDERICK BREITENFELD.
